UNITED STATES PATENT OFFICE.

JOHN A. ORRALL, OF WINTHROP, MASSACHUSETTS.

DAY-BY-DAY BOX.

1,215,572.

Specification of Letters Patent. Patented Feb. 13, 1917.

Application filed April 1, 1916. Serial No. 88,260.

To all whom it may concern:

Be it known that I, JOHN A. ORRALL, of Winthrop, in the county of Suffolk and State of Massachusetts, have invented certain new and useful Improvements in Day-by-Day Boxes, of which the following is a specification.

This invention relates to devices frequently termed filing systems, and refers particularly to devices of this character which are kept in convenient locations and noticeable positions, such as on the desk of a business or professional man, for daily reference, especially as a reminder of special matters which he wishes to attend to day by day.

The object of my invention is to provide an improved device of this character which will, to a considerable extent, serve the purpose of a business man's secretary so far as an inanimate object can serve such purpose.

In attaining this object, I provide a series of 366 disconnected and individually removable cards, one for each day of the year (including the 29th of February), each card having a tab bearing the name of a month (or the abbreviation of such name), and a month day indicated by numerals, and preferably nothing else. By omitting any indication of the days of a week, the series may be used year after year without confusion, in a manner somewhat similar to what is known as a perpetual calendar. This series of cards is so fitted in a box or case that every tab is visible so that the card for any future date may be lifted or removed for making any entry on the face of it to serve as a reminder when that date is reached, and the card then restored to its proper place, and also so that the entire face of the front card is exposed to view, whereby the user need only shift each front card after that day has passed, to the back of the series, and thus expose all the memoranda of matters to be attended to the next or current day.

Of the accompanying drawings which illustrate one embodiment of my invention, but to which embodiment I do not specifically limit myself:—

Figure 1 is a perspective view of the case or box with the front member open and the dust-protecting cover removed and with a sufficient number of the tab-cards in position to illustrate my invention, the rear portion

of the box being broken away because the horizontal depth of the box is unimportant.

Fig. 2 represents a vertical section from front to rear of the box, closed as when not in use.

Fig. 3 is a front view, enlarged, of some of the cards of the series, to illustrate a preferred arrangement of the tabs.

Similar reference characters indicate similar parts in all of the views.

The box or case which contains the series of cards comprises a bottom 12, rear wall 13, sides 14 and a front wall 15 which has a hinged connection with the receiving portion of the box as by means of pivots 16. One or more stops 17 projecting inwardly from the sides 14 serve to arrest the front wall or door 15 when the latter is in box-closing position as shown in Fig. 2.

For the purpose of preventing the accumulation of dust upon and between the cards, when the device is not in use, a suitable movable cover 18 is employed as indicated in Fig. 2, which cover may be either bodily removable or having a hinged connection so that it may be swung back.

Rising from the bottom 12 at a little distance back from the front edge thereof is a strip 19. Another strip 20 nearer the front of the bottom, and a division strip 21, coat with the front of the strip 19 in forming receptacles for small articles useful in daily business, such as pins or postage stamps.

The front member 15 is provided with a groove 22 to form a pen or pencil recess for use when the front is in the open position indicated in Fig. 1. The inner face of the member 15, which becomes the upper surface when said member is open, is provided with angular pockets 23 to receive the corners of any suitable number of paper memoranda slips 24.

The cards 25 which may be ruled in any preferred manner are provided with tabs 26. That is, each card has a tab, and the tabs of the different cards of the series are arranged so that all of the tabs are easily visible when the box is open. A convenient arrangement of the tabs is to have them formed in several sections, each section comprising sixteen cards with the tabs projecting from the cards in step by step lateral relationship as indicated by comparing Figs. 1 and 3. This arrangement renders it certain that there will be sufficient space

between the cards of each section so that none of the tabs will be concealed by tabs of other cards which are in front thereof. There is a card for every day of the year, and they are all disconnected so that any card can be lifted or removed for the purpose of making memoranda thereupon and then returned to place, and so that each front card when the day has passed, can be shifted over to the back of the series to expose the card bearing the date of the next day. As shown in Fig. 3, each tab bears only the month day and not a week day. That is, each tab bears the name or indication of a month, and a single day of that month, there being no indication of any day of the week. This enables the system of cards to be used year after year.

As indicated in Fig. 2, the bottom 12 is inclined upwardly and rearwardly, and the rear wall 12 is inclined rearwardly. This arrangement provides for the support of the cards in position to facilitate a visual examination of the tabs of the series, in better manner than if the cards were to stand vertically in the same horizontal plane. While the stops 15 serve to determine the closed position for the front wall 15, they also prevent the cards from tilting too far forwardly out of the box, when the box is open, and the user desires to separate the series of cards at some point in order to draw out or restore a card or when drawing the entire series forward far enough to permit the shifting of the front card in behind the rearmost card of the series.

Of course it will be readily understood that the user, instead of always making memoranda of matters to be attended to in the future, on the cards for those future dates, may make memoranda on one of the slips 24 or any other slip of paper and insert it in the proper place between cards of the series.

I desire to have it understood also that I

do not limit myself to the employment of tab cards alone, since I may use, in addition thereto, any other indicator or filing system devices which, in such case, would preferably be inserted between the rearmost tab card and the rear wall of the box.

Having now described my invention, what I claim is:

1. A card system of the character described, comprising a series of separate and individually shiftable tab cards equaling the number of days of a year, the tab of each card bearing the designation of a month and the day of a month, and a container constructed to support the entire series of cards with all of their tabs and the face of the front card in visible position.

2. A card system of the character described, comprising a series of separate and individually shiftable tab cards equaling the number of days of a year, the tab of each card bearing the designation of a month and the day of a month, and a container constructed to support the entire series of cards with all of their tabs and the face of the front card in visible position, said container having an upwardly and rearwardly inclined bottom.

3. A card system of the character described, comprising a series of separate and individually shiftable tab cards equaling the number of days of a year, the tab of each card bearing the designation of a month and the day of a month, and a container having a hinged front, an upwardly and rearwardly inclined bottom, and a movable cover, whereby, when the cover is displaced and the front swung forward, all of the card tabs and the face of the front card may be viewed without displacing the cards from their relative positions.

In testimony whereof I have affixed my signature.

JOHN A. ORRALL.
